(57) CLAIM

The ornamental design for a beverage opener, as shown and described.

DESCRIPTION

FIG. 1 is a perspective view of a beverage opener;
FIG. 2 is a top plan view thereof;
FIG. 3 is a bottom plan view thereof;
FIG. 4 is a left side elevational view thereof;
FIG. 5 is a right side elevational view thereof;
FIG. 6 is a front elevational view thereof; and,
FIG. 7 is a rear elevational view thereof.
The broken lines depict portions of the beverage opener which form no part of the claimed design.
